UNITED STATES PATENT OFFICE.

EMERY WINCA, OF CLEVELAND, OHIO.

SPARK INTENSIFIER.

Application filed December 12, 1921. Serial No. 521,803.

To all whom it may concern:

Be it known that I, EMERY WINCA, a citizen of the United States, residing at Cleveland, in the county of Cuyahoga and State 5 of Ohio, have invented certain new and useful Improvements in a Spark Intensifier, of which the following is a specification.

My object is to provide a spark intensifier of superposed elements adapted to be easily 10 assembled and separated to facilitate manufacture, inspection and repairs, and a further object is to provide a simple form of spark intensifier which will be inexpensive to produce and convenient to attach and use 15 in connection with the spark plugs of internal combustion engines.

In the accompanying drawing, Fig. 1 is a side view of my improved spark intensifier attached to a spark plug. Fig. 2 is a plan 20 view of the spark intensifier, and Fig. 3 is a longitudinal section thereof on line 3—3 of Fig. 2. Fig. 4 is a plan view of the spark intensifier opened to give free access to the 25 sparking elements. Figs. 5 to 9 inclusive, are perspective views of the separate elements composing the device.

The invention comprises three separate flat pieces of fiber, 2, 3 and 4, respectively, superposed and fastened together at their 30 corresponding ends by a rivet 5, or its equivalent. All said three pieces possess separate central openings adapted to register with each other to provide a common air passage, and the opening 6 in piece 4 is of smaller 35 diameter than the openings 7 and 8, respectively, in pieces 2 and 3, to induce a slight flow of air through the openings. The bottom face of piece 2 is provided with a tapered stepped channel 9, extending from 40 opening 7 to one end edge thereof, and channel or recess 9 is adapted to receive and confine a flat metal conductor 10 having a raised sparking point 11 at its inner and smaller end, and which sparking end projects 45 into the center of opening 7 when said conducting element 10 is secured within recess 9. The outer end of conducting element 10 has an opening 12 to attach an electric conductor thereto or to permit this element 50 to be attached to the central screw terminal 14 of a spark plug 15, see Fig. 1.

The middle fiber piece 3 is also provided with a tapering channel or recess 16 in its upper face at one end thereof, and the inner 55 end of this channel or recess terminates in a

slot or opening 17 adjacent central opening 8. A second metal conducting element 18 of tapering form longitudinally and offset at its smaller end 19, is adapted to occupy recess 16 in piece 3, the offset end 19 being 60 projected through slot 17 into central opening 8 where the raised sparking point 20 thereon is held in closely-spaced relation to the sparking point 11 on conductor 10. The outer end 21 of conducting element 18 is perforated to facilitate the attachment of an electric wire or conductor thereto, and both of the conducting elements 10 and 18 have openings at their middle adapted to 65 receive the round bosses 22 and 23 located centrally in channels 16 and 9, respectively. Rivet 5 passes through boss 22 and a screw 24 extends through piece 2 and its boss 23 and through middle piece 3 and into piece 4 70 to fasten and clamp the parts together when assembled as shown in Fig. 3.

In use when this device is applied to a spark plug, the electric current in passing to the plug jumps the gap between points 11 75 and 20 and creates a stronger and more intense sparking result at the sparking terminals of the spark plug. To obtain the most effective operating results under different conditions or with different types of 80 spark plugs, it is necessary to adjust or alter the working relation of the sparking points 11 and 20. Further, to obtain the best results after continued use of the device it is also desirable to clean and brighten the 85 opposing points at intervals. I facilitate adjustments and bending of the points towards and away from each other, and give free access to the points, when screw 24 is removed to permit the separate pieces to swivel 90 or turn on pivot pin 5 into an open position substantially as shown in Fig. 4. In this position of the parts, conducting element 10 can be bodily removed if desired.

What I claim, is

A spark intensifier, comprising three superposed flat pieces having central registering openings and two of said pieces having stepped channels in their meeting faces, separate metal conductors having offset ends 100 provided with sparking points extending into said central openings, and means pivotally uniting said pieces together.

In testimony whereof I affix my signature.

EMERY WINCA.
